UNITED STATES PATENT OFFICE.

WILLIAM ARTHUR BENNETT, OF KENSINGTON, LONDON, ENGLAND.

KINEMATOGRAPH-TARGET.

1,081,943.

Specification of Letters Patent. Patented Dec. 23, 1913.

Application filed November 8, 1911. Serial No. 658,412.

To all whom it may concern:

Be it known that I, WILLIAM ARTHUR BENNETT, of Kensington, in the county of London, England, director of public companies, have invented a certain new and useful Improvement in Kinematograph-Targets, of which the following is a specification.

My invention relates to improvements in target apparatus in which a kinematograph is employed whereby a series of moving pictures is projected on to a perforable screen arranged so that the actual point struck by a bullet aimed at the screen may be shown in its correct relation to the image which was before the marksman at the instant of firing.

The objects of my invention are, first, to arrest the kinematograph at the instant of firing; second, to enable a series of shots to be fired without arresting the kinematograph until the last shot is fired and to provide for the identical pictures aimed at being restored to the screen when firing has ceased; and, third, to indicate or ascertain the accuracy of shots when firing is carried out with raised sights or allowance is made for "windage."

I attain these objects by the mechanism illustrated in the accompanying drawings in which:—

Figure 1. is a diagrammatic vertical section of a target; Fig. 2. is a plan view of Fig. 1; Fig. 3. is a diagram of the electrical connections between a kinematograph and a fire-arm; Fig. 4. is a detail view of an electromagnetic clutch; Figs. 5 and 6 are details of an attachment for a fire-arm; Fig. 7 is a diagrammatic elevation of the registering mechanism; Fig. 8. is an elevation partly in section of the means for displacing the picture relatively to the screen and Fig. 9. is an end elevation of Fig. 8.

Similar letters refer to similar parts throughout the several views.

Referring to Figs. 1 and 2, the target comprises screens 1 and 2 mounted upon rollers 3 and 4 connected by means of pulleys or wheels and belts or chains 5 and 6. Each set of rollers is actuated by means of a belt or chain 8 and 9 and hand wheels 10 and 11 so as to produce a relative motion of the screens for the purpose of obturating shot holes in the known manner. In the vicinity of the bullet proof plates 12, 13 and 14 wood screens 15 and 16 are arranged to

prevent splashing of the bullets, and at a convenient point a source of light 17 serves to illuminate the space behind the screens. The hand wheels 10 and 11 and a switch 18 for controlling the light are arranged in a pit 7 in front of the target. This pit affords protection to the marker and enables him to ascertain the value of a shot, by means of the beam of light which passes through a hole, more readily than a marker at the firing point. The kinematograph may be located either at the firing point or in the pit.

In order to enable the result of a shot to be compared with the picture aimed at so that the actual point struck by the bullet may be shown in its correct relation to the image which was before the marksman at the time of firing, the arrangement illustrated in Figs. 3, 4, 5, and 6 is employed in combination with that above described.

In the diagram of Fig. 3, 19 indicates a source of current, 32 the coil of an electro-magnetic clutch in the film-driving train of a kinematograph, 21 a one-way switch, 21' a two-way switch and 22 a contact device mounted upon the trigger guard of a fire-arm. When the trigger is pulled contact device 22 completes the circuit of coil 32 and the kinematograph is arrested thereby retaining the image aimed at upon the screen 1.

The clutch in the film-driving train shown in Fig. 4 comprises a crown wheel clutch member 23 mounted on a shaft 24 driven by a chain (not shown) and chain wheel 25. The shaft 24 has a bearing in the sleeve 26 carried by the frame 27. A wheel 28 is mounted loosely upon sleeve 26 which latter is surrounded by a coil 32 inclosed within a shell of magnetic material 33. The arrangement forms an iron clad magnet of which the wheel 28 is the armature. Disks 34 and 35 and a spring 36 are located between coil 32 and wheel 28 in such a manner that the spring normally forces wheel 28 into that position in which the teeth 31 engage the driving wheel 23 whereby the film is driven in the usual manner. When coil 32 is energized by the closing of the trigger contact 22, wheel 28 is disengaged from wheel 23 and positively locked in a stationary position by reason of the teeth 30 engaging with teeth 37 on the shell 33.

To maintain the clutch in the energized condition, I provide a maintaining switch

60

in the magnet circuit. This switch consists of a contactor coil 20^a connected to one terminal of coil 32 and to a contact 20^b which latter is connected with one element of the trigger contact 22. The contact 20^c is connected to the other element of the trigger contact. The contactor 20^a bridges the contacts 20^b and 20^c when the coil 20^a is momentarily energized and thereby short-circuits the trigger contact and maintains the clutch magnet coil 32 in the energized condition. To start the kinematograph again switch 21 is momentarily opened and the apparatus is again in condition to be once more arrested when the trigger contacts are closed. If the frame 27 is not magnetic the shell 33 is provided with a plate or bar to complete the magnetic circuit.

The trigger contact shown in Figs. 5 and 6 comprises a fragment of a rifle 38 and a trigger guard 39 to which the trigger 40 is pivoted. The contact proper consists of a socket 41 provided with a clip of insulating material 42 and a metallic spring clip 43. Flexible conductors 44 and 45 enter the socket the former being continued at 44^a within the clip 42 and connected to a contact 46. Conductor 45 is "grounded" on the clip 43 or socket 41. When the trigger is pulled a circuit will be completed through the flexible leads, the trigger contact and the clutch magnet.

When a series of shots are fired collectively or successively it is desirable that the kinematograph should not be arrested after the first shot is fired and to this end I provide the arrangement shown in Fig. 7, in which 47 is a reel mounted in the shaft of the film-driving sprocket and 48 is a reel mounted upon a conveniently situated pin 49. The reel 48 carries a roll of paper one end of which is connected to reel 47. When the kinematograph is running the paper is wound on to reel 47 in synchronism with the running of the film. The armature 51 of a magnet 52 carries a stylus 53 which when the magnet is energized engages the strip 50 and marks same. The strip 50 passes in front of a platen 54. The winding of magnet 52 is connected on the one hand with one of the trigger contacts and on the other hand with one terminal of the two-way switch 21' as shown in Fig. 3. Where this switch is thrown over the marking magnet 55 is put in circuit and each time the trigger is actuated the strip or roll 50 will be marked. By reversing the kinematograph each mark can be brought into register with an index on the platen and each picture 60 aimed at will be restored to the screen. The strip 50 may be divided into divisions corresponding with pictures or portions of pictures on the film.

In cases where the apparent distance is 65 beyond point blank range and it is desired

to aim above the object or shoot with raised sights or allow for "windage" I provide means for displacing the picture aimed at relatively to the screen by a predetermined amount proportional to the allowance to be made for the assumed range or "windage." 70 These means are illustrated in Figs. 8 and 9, in which 55 represents diagrammatically a kinematograph mounted upon a table 56. The table is rotatably mounted upon a supporting rod 57 screwed into a standard 58. A worm wheel 59 keyed to rod 57 engages a worm 60 having a bearing in the bracket 61. The hand wheel 62 serves to rotate the worm and wheel. The bracket 61 is loosely mounted between collars on the rod 57 and is provided with an arm 63 carrying at its upper extremity a pinion 64 actuated by a hand wheel 65. The pinion 75 engages teeth on the under side of table 56. 80

By manually rotating wheel 62, the table 56 may be raised or lowered thereby raising or lowering the picture upon the screen after a shot has been fired by an amount proportional to the allowance to be made for 90 firing with the back sight raised.

Rotation of the table during vertical adjustment is prevented by reason of the pinion 64 engaging the teeth on the table. Allowance for "windage" is made after a shot 95 is fired by displacing the picture on the screen to right or left by means of wheel 65. This wheel provides for the angular displacement of the table and kinematograph but the rod 57 is prevented from turning 100 by reason of the friction between the worm 60 and wheel 59. The fork 66 secured to the standard 58 prevents angular displacement of the bracket 61.

The means for displacing the picture 105 aimed at relatively to the screen also contemplates according to my invention a device for sliding the kinematograph to right or left when adjusting for "windage" allowance and for turning it about a horizontal axis to adjust for shooting with raised sights.

After the picture has been displaced proportionately to the windage adjustment of the sights, the position of the bullet hole 115 will show the accuracy of the aim directly on the picture as though the picture had been originally shot at under the actual conditions of distance and windage.

Although I have described one specific 120 embodiment of my invention I do not wish to be limited thereto since the invention may be carried into effect in a variety of ways without departing from the spirit thereof.

What I claim and desire to secure by Letters Patent is:—

1. The combination with a kinematograph, of a plurality of relatively movable screens, means for indicating the point of impact of a bullet, means controlled by the opera- 130

- tion of a firearm whereby the motion of the kinematograph is arrested, and means for displacing the picture in a plurality of directions relatively to the screen.
5. 2. The combination with a kinematograph, of a plurality of relatively movable screens, means for indicating the point of impact of a bullet, means controlled by the operation of a firearm to arrest the motion of the kinematograph at the instant of firing, and means for displacing the picture in a plurality of directions relatively to the screen comprising mechanism for elevating and lowering the kinematograph.
10. 3. The combination with a kinematograph, of a plurality of relatively movable screens, means for indicating the point of impact of a bullet, means controlled by the operation of a firearm whereby the identical picture aimed at may be restored to the screen, and means for displacing the picture in a plurality of directions relatively to the screen comprising mechanism for turning the kinematograph about a vertical axis.
15. 4. The combination with a kinematograph, of a plurality of relatively movable screens, means for indicating the point of impact of a bullet, means controlled by the operation of a firearm whereby the motion of the kinematograph is arrested, and means for displacing the picture relatively to the screen comprising mechanism for elevating and lowering and mechanism for turning the kinematograph about a vertical axis.
20. 5. The combination with a kinematograph, of a plurality of relatively movable screens, means for indicating the point of impact of a bullet, means controlled by the operation of a firearm whereby the motion of the kinematograph is arrested, means for displacing the picture relatively to the screen comprising a table for the kinematograph, a screw threaded support for the table, a mounting for said support, a worm and wheel whereby the support is rotated and the table is moved vertically, teeth on the table, and a pinion engaging said teeth whereby the table is displaced angularly independently of its support.
25. 6. The combination with a kinematograph having a film driving train, of a plurality of relatively movable screens, means for indicating the point of impact of a bullet, an electro-magnetic clutch in the film driving train of the kinematograph, a source of current to energize said clutch to stop the kinematograph, a contact device in the circuit of the clutch magnet, said contact device being mounted upon the trigger guard of a firearm, and means for displacing the picture relatively to the screen.
30. 7. The combination with a kinematograph having a film driving train, of a plurality of relatively movable screens, means for indicating the point of impact of a bullet, an electro-magnetic clutch in the film driving train of the kinematograph, a source of current to energize said clutch to stop the kinematograph, a contact device in the circuit of the clutch magnet, said contact device being mounted upon the trigger guard of a firearm, and means for displacing the picture relatively to the screen.
35. 8. The combination with a kinematograph, of a plurality of relatively movable screens, means for indicating the point of impact of a bullet, a strip of paper moved synchronously with the film, a magnet, a stylus on the armature of said magnet, mechanism controlled by the operation of a firearm for energizing the magnet whereby the stylus is caused to engage said strip of paper, and means for displacing the picture by a predetermined amount relatively to the screen.
40. 9. The combination with a kinematograph, of a plurality of relatively movable screens, means for indicating the point of impact of a bullet, means controlled by the operation of a firearm whereby the motion of the kinematograph is arrested, a table for the kinematograph, a support therefor, and means for displacing said table angularly independently of said support.
45. 10. The combination with a kinematograph, of a plurality of relatively movable screens, means for indicating the point of impact of a bullet, means controlled by the operation of a firearm whereby the motion of the kinematograph is arrested, a table for the kinematograph, a screw threaded supporting rod therefor, a stationary mounting for said rod, a worm, and worm wheel, a hand wheel whereby the support is rotated and the table adjusted vertically, and means for displacing said table angularly about a vertical axis independently of said support.
50. 11. The combination with a kinematograph, of a plurality of relatively movable screens, means for indicating the point of impact of a bullet, an electromagnetic clutch in the film driving train of the kinematograph, a source of current for energizing said clutch to stop said kinematograph, a contact device in the circuit of the clutch magnet mounted upon the trigger guard of a firearm, means for displacing the picture relatively to the screen, said means comprising a table for the kinematograph, a support therefor, a mounting for said support, a worm and worm wheel and hand wheel whereby the support may be adjusted vertically, and means for displacing said table angularly independently of said support.
55. 12. The combination with a kinematograph, of a plurality of relatively movable perforable screens, a source of light located

4

behind said screens, an electromagnetic clutch in the film driving train of the kinematograph, a firearm, a contact device on said firearm controlling said electromagnetic clutch, a source of current for energizing said clutch, and electromagnetic means whereby the clutch is maintained energized after said contact device opens.

13. The combination with a kinematograph, of a plurality of relatively movable perforable screens, a source of light located behind said screens, a strip of paper moved

in synchronism with the film, a magnet, a stylus on the armature of said magnet, contacts in the magnet circuit controlled by the 15 operation of a firearm, a platen adjacent said strip of paper and stylus a table for the kinematograph, a support for the table, and means for independently adjusting said table vertically and angularly.

WILLIAM ARTHUR BENNETT.
